UNITED STATES PATENT OFFICE.

ROBERT A. BOWEN, OF SPOKANE, WASHINGTON.

BOX-CAR DOOR.

Application filed December 24, 1920. Serial No. 432,917.

To all whom it may concern:

Be it known that I, ROBERT A. BOWEN, a citizen of the United States of America, residing at N. 4013 Crestline Street, Spokane, 5 in the county of Spokane, State of Washington, have invented new and useful Improvements in Box-Car Doors, of which the following is a specification.

This invention pertains to box cars, and 10 has for its object to provide a more practical, durable and otherwise efficient means for closing the opening in a box car. Special objects are to provide a means for suspending the door that can not become detached, to provide a means for holding the door against the side of the car when the same is open just as securely as the door can be held over the opening, to provide means for guiding the door in closing so that the 15 door will always occupy the same vertical position, so that the same is adjusted to position for sealing, to provide strengthening and protective means for the door and means whereby the door will not stick and be difficult of opening by reason of the swelling of 20 the wood from moisture. The invention will be hereinafter particularly described and illustrated in the accompanying drawings in which Figure 1 is a broken-away 25 side elevation of a box car showing my improved construction.

Figure 2 is a vertical sectional view taken on the line 2—2 of Figure 1, Figure 3 is an enlarged detail view of a pin used in fastening and sealing the door. Figure 4 is a vertical sectional view taken on the line 4—4 of Figure 1, Figure 5 is a horizontal sectional view taken on the line 5—5 of Figure 1 and Figure 6 is an enlarged fragmental 30 view of one of the strips at the side of the door opening. In a detail description in which like numerals refer to like parts throughout the several views, the side wall 10 of the car is of ordinary construction. 35 An opening 11 is provided in the car side 10 and vertical strips 12 and 13 mounted one on each side of the opening 11. A further vertical strip 14 is mounted at a distance from the strip 13 equal to the distance of the 40 strip 13 from the strip 12 in order that the door 15 may be shifted from its shown closed position between the strips 12 and 13 to the space 16 between the strips 13 and 14 when it is desired to open the door. Mount-

ed in spaced relation to each other along the 55 car side 10 and near the top thereof are brackets 17, 18 and 19 in which is mounted a rod 20 held in position by pins 21. Hangers 22 are secured to the door 15 and have portions 23 extending outwardly beyond the 60 other edges of the door 15 and upwardly extending portions 24 through which the rod 20 is extended and by means of which the door 15 is slidably suspended in such a manner that there can be no disconnection in 65 sliding the door 15 from one position to another. A jam 25 secured to car side 10 near the top of the opening 11 coming in contact with one of the hangers 22 serves to position the door 15 laterally when closing and a like jam 26 mounted on the car side 10 near the top thereof and extending over the strip 14 serves to position the door 15 in the space 16 laterally. 70

Mounted transversely across the door 15 and secured thereto as by rivets 27 are supporting metal portions 28. The portions 28 are provided with U-shaped openings 29. Mounted on the strips 12, 13 and 14 are keepers 30. When the door 15 is swung over the opening 11 or space 16 and dropped into the opening 11 or space 16, these keepers 30 striking into the U-shaped openings 29 of the portions 28 in the vertical adjustment of the door serve to guide the door always to the same vertical position, thereby transferring the weight of the door, to a great extent, from the rod 20 to the strips 12, 13 and 14. Pins 31 secured by chains 32 to the portions 28 are passed through openings through the portions 28 and through the keepers 30 and serve to help hold the door 15 in a rigid closed position. Openings 33 in the bottom of the pins 31 provide means for sealing the door 15 closed. 85

A keeper 34 beneath the opening 11 in the car side 10 and a keeper 35 beneath the space 16, provide means for holding the door 15 against swinging outwardly from the car, a pin 36 secured to the door 15 by a chain 37, being provided to engage the keepers. The end and side edges of the door 15 are covered by a metal casing 38 secured thereto by rivets 39, and serving as a protection for the door as well as to prevent the door from sticking by reason of swelling from moisture. Likewise and for the same purpose, a metal covering 40 is provided over the 90 95 100 105

threshold 41. A water shed 42 extends the full length of the construction. To the outside of the door 15 is secured a handle 43.

The outward extensions 23 of the hangers 22 are necessary to facilitate the transfer of the door 15 from the opening 11 to the space 16 and vice versa. When the door 15 is closed as is shown in the drawings, and it is desired to open the same, the pins 31 and 36 are manually removed from the keepers 30 and 36 respectively, the lower end of the door 15 manually raised outwardly a foot or eighteen inches by means of a hand hold on the handle 43 and the door manually shifted along the rod 20 until one of the hangers 24 strikes against the bracket 19 and the other against the bracket 18. The door 15 is then dropped to position in the space 16 and the pin 36 inserted in the keeper 35 and one of the pins 31 in the keeper 30 on the strip 13.

When it is desired to again close the door 15, substantially the same process is gone

through, modified only to place the door and its securing parts in the positions shown in 25 the drawings.

What is claimed is:

In a box car having a side door opening, strips vertically mounted, one on each side of the opening, a door adapted to fit the 30 opening with its sides adapted to fit against said strips, a rod horizontally mounted on the side of the car above the door, hangers attached to the door having portions slidably engaging said rod, keepers on said 35 strips, supports arranged transversely on the door having U shaped guides therein adapted to engage the keepers on the strips and pins for fastening said supports and keepers together, whereby the weight of the 40 door is partially supported by said strips.

In testimony whereof, I affix my signature in presence of a witness.

ROBERT A. BOWEN.

Witness:

L. L. WESTFALL.
